UNITED STATES PATENT OFFICE.

DAVID J. RORABECK, OF RYEGATE, MONTANA.

RACK FOR DRYING PHOTOGRAPHIC FILMS.

1,072,654.

Specification of Letters Patent.

Patented Sept. 9, 1913.

Application filed May 5, 1913. Serial No. 765,656.

To all whom it may concern:

Be it known that I, DAVID J. RORABECK, a citizen of the United States, residing at Ryegate, in the county of Musselshell and State of Montana, have invented certain new and useful Improvements in Racks for Drying Photographic Films, of which the following is a specification, reference being had to the accompanying drawings.

This invention relates to new and useful improvements in photographic and developing apparatus and more particularly to a rack for drying films and my object is to provide a device of this character which is readily adapted for use in connection with films of various sizes.

A further object of the invention resides in providing a device which is designed to hold a plurality of films of various sizes and a still further object resides in providing a device which is simple and durable in construction, inexpensive to manufacture and one which will be very efficient and useful in operation.

With these and other objects in view, the invention consists in the novel features of construction, combination and arrangement of parts as will be hereinafter referred to and more particularly pointed out in the specification and claims.

In the accompanying drawings forming a part of this application, Figure 1 is a perspective view of the device partly assembled showing certain of the auxiliary frames in their raised positions and certain other of said auxiliary frames in their lowered positions. Fig. 2 is an end elevation of the same partly in section. Fig. 3 is a longitudinal section through one of the auxiliary frames. Fig. 4 is a perspective view of one of the spring clamping members used in connection with the side bars of the main frame. Fig. 5 is a fragmentary perspective view of the central supporting strip used on the main frame; and Fig. 6 is a perspective view of one of the finger pieces used in connection with one of the spring clamping members.

In describing my invention, I shall refer to the drawings in which similar reference characters designate corresponding parts throughout the several views and in which—

1 indicates a frame of substantially rectangular design consisting of the end sills 2 and the side bars or clamping members 3 which are secured to the former by means of

the metal clips 4. Removably secured to the upper faces of the end sills 2, is a metal strip or plate 5 which has numerous portions struck up therefrom as shown at 6 to form ears and extending longitudinally through said ears or struck up portions 6, for the full length of the frame 1, is a shaft 7 which forms a hinge or pivot pin for portions of the device to be hereinafter described. Pivotally mounted on this shaft 7, and extending from both sides thereof, are a plurality of rectangular frames 8, the same being arranged between certain of the struck up ears 6 of the plate or strip 5 to prevent lateral movement of the same on said shaft and encircling said shaft, are a plurality of coil springs 9, the one end of each of which is engaged with the stationary plate or strip 5, while the opposite end thereof is engaged with a frame 8. The normal tendency of these springs 9 is to force said frames 8 upwardly so that the outer free ends thereof will be raised and spaced above the outer side bars 3 of the frame 1 and in order to limit the upward swinging movement of said frames 8, the inner pivotal ends of the latter are provided with the projections 10 which are adapted to contact with the upper faces of the plate or strip 5 when said frames 8 have reached their predetermined raised positions. I have provided means to retain said swinging frames 8 in their lowered positions in contact with the side bars 3 of the frame 1 and to this end, said outer side bars are provided, at regular intervals on the inner faces thereof, with leaf springs 11. These leaf springs are secured at their lower ends to the inner faces of the side bars and project upwardly from the inner faces thereof, the extreme free edges thereof projecting somewhat inwardly to form finger pieces. An opening 12 is provided in each of the leaf springs which is adapted to receive therein a pin 13 carried on the outer end bar of each of the frames 8, said pin projecting inwardly from the inner face of the latter. It will be seen from this construction that as a frame 8 is forced downwardly, the pin 13 on the outer end bar thereof will contact with the outer face of the projecting portion of the leaf spring 11 and when the lower edge of the outer bar of said frame contacts or rests on the upper end of the inside bar 3, the pin 13 will spring into locked position in the opening 12 of said leaf spring 11. The frame will

thus be retained in its lowered position until such time when the leaf spring is released from engagement with said pin 13, whereupon said frame will be automatically disposed to its raised position, under tension of the spring 9.

I have also provided means for the clamping of films to the side bars 3 and the outer end bars of each of the frames 8 and to this end, leaf springs 15 are secured to the inner faces of the side bars 3, the same being bent below said side bars to project in front of said side bars in spaced relation thereto. These arcuately bent leaf springs are arranged in pairs and secured to the free end of each pair is a clamping bar or plate 16 which is provided with a plurality of inwardly projecting teeth 17, said teeth being adapted to be forced under tension of the springs 15 against the outer faces of the side bars 3. Each of the clamping bars or plates 16 is also provided with an outwardly projecting finger piece 18, while additional finger pieces 19 are also secured to the outer faces of the side bars 3 to coöperate with said finger pieces. By pressing the finger pieces 18 and 19 together, the teeth 17 on the clamping bars 16 will be sprung away from the outer faces of the side bars 3.

Secured to the inner face of the outer end bar of each of the frames 8, is a pair of leaf springs 20 which are bent around the upper edge of said outer end bar and disposed downwardly in spaced relation to the outer face thereof. Each pair of these springs 20 on the frames 8, is connected at the free ends thereof by a clamping bar or plate 21 which has inwardly projecting teeth 22, the latter being adapted to contact with the outer face of the end bar of the frame under tension of said springs 20. Each clamping bar or plate 21 is provided with a downwardly curved finger piece 23 and the outer face of each of the end bars of the frames 8 is provided with an additional downwardly projecting finger piece 24 to coöperate with the finger piece 23. By forcing said finger pieces 23 and 24 together, the teeth 22 on the clamping plate or bar 21, will be drawn away from the outer bar of the frame 8.

From the above description, it will be seen that substantial spring clamping jaws are provided on the side bars of the main frame and on the outer ends of the swinging or auxiliary frames and in order to dry a plurality of films on the rack, said swinging auxiliary frames are first released from their lowered positions by releasing the leaf springs 11 from their engagement with the pins 13, thus allowing the free ends of the frames 8 to be forced to their raised positions under tension of the springs 9. The one end of each film is then clamped to the side bar 3 by springing the teeth 17 of the

clamping plate 16 into engagement therewith. By grasping the finger pieces 23 and 24 and pressing them together, each frame 8 is forced downward until the free end thereof is near enough to the side bar to admit the other end of the film to be introduced between the teeth 22 of the clamping bar 21, and the outer bar or auxiliary frame. Then by releasing the finger piece 23, the upper end of the film will be clamped tightly to the outer bar of the frame 8, by engagement of the teeth 22 therewith and by releasing the finger piece 24, the end bar of said frame 8 will be raised upward under the tension of the spring 9, until said film is taut. Through this medium, films may be of various sizes and, in any instance, the same will be readily fitted to this device to be drawn taut and dried in the rack.

From the foregoing it will be seen that I have provided a device which is simple and durable in construction, inexpensive to manufacture and one which will be very efficient and useful in operation, and while I have particularly described the elements best adapted to perform the functions set forth, it is obvious that various changes in form, proportion and in the minor details of construction may be resorted to without departing from the spirit or sacrificing any of the principles of the invention.

Having thus described this invention, what is claimed is:—

1. A film drying rack comprising a main frame, a plurality of auxiliary frames hingedly mounted thereon, means in connection with said auxiliary frames to normally force the outer ends of the same in raised position with respect to the main frame, and clamping members in connection with the outer ends of said auxiliary frames and portions of said main frame adapted to coöperate with one another.

2. A rack of the class described comprising a main frame, a plurality of auxiliary frames hingedly mounted thereon, means in connection with said auxiliary frames to normally force the same in raised position with respect to the main frame, means for locking said auxiliary frames in their lowered positions in engagement with said main frame, and clamping members on said main and auxiliary frames adapted to coöperate with one another.

3. A rack of the class described comprising a main frame of substantially rectangular design, a plurality of auxiliary frames hinged centrally on said main frame, the free ends of said auxiliary frames being adapted to rest upon the side bars of said main frame, means in connection with said auxiliary frames to normally force the same to their raised positions, means for locking said auxiliary frames in their lowered positions in contact with the side bars

of said main frame, and clamping members carried on the outer ends of said auxiliary frames and on the side bars of said main frame adapted to coöperate with one another.

5. A rack of the class described comprising a main frame of substantially rectangular design, a central longitudinal strip mounted thereon, a plurality of auxiliary frames hinged at their inner ends on said strip and adapted to have their outer ends rest on the side bars of said main frame, spring means in connection with said strip and auxiliary frames to normally force the latter to their raised positions, means to limit the upward swinging movement of said auxiliary frames, means for locking said auxiliary frames in their lowered positions in contact with the side bars of the 10 main frame, and clamping members on the outer ends of said auxiliary frames and on the side bars of said main frame adapted to coöperate with one another.

20. 6. A rack of the class described comprising a main frame of substantially rectangular design, a central longitudinal strip mounted thereon, a plurality of auxiliary frames hinged at their inner ends on said strip and adapted to have their outer ends 25 raised in contact with the side bars of the main frame, spring means in connection with the hinged ends of said auxiliary frames to normally force the same to their raised positions, means to limit the upward 30 swinging movement of said auxiliary frames, spring locking means for retaining 35

said auxiliary frames in their lowered positions in contact with the side bars of the main frame, and spring clamping members carried on the outer ends of said auxiliary 40 frames and on the side bars of said main frame adapted to coöperate with one another.

7. A rack of the class described comprising a main frame of substantially rectangular design, a central longitudinal strip mounted thereon, a plurality of auxiliary frames hinged at their inner ends on said strip and adapted to have their outer ends contact with the side bars of the main 45 frame, spring means in connection with the hinged ends of said auxiliary frames to normally force the same to their raised positions, projections formed on the inner ends of said auxiliary frames adapted to contact 50 with said strip to limit the upward swinging movement of said auxiliary frames, spring locking means in connection with said auxiliary frames and the side bars of said main frame to lock the former in their 55 lowered positions in contact with the latter, and spring clamping members in connection with the outer ends of said auxiliary frames and the side bars of said main frame adapted to coöperate with one another. 60

In testimony whereof I hereunto affix my signature in the presence of two witnesses.
